H. BELFIELD.
VALVE.

No. 105,027.

Patented July 5, 1870.

United States Patent Office.

HENRY BELFIELD, OF PHILADELPHIA, PENNSYLVANIA.

Letters Patent No. 105,027, dated July 5, 1870.

IMPROVEMENT IN VALVES.

The Schedule referred to in these Letters Patent and making part of the same.

I, HENRY BELFIELD, of Philadelphia, county of Philadelphia, State of Pennsylvania, have invented an Improved Straight-way Stop-Valve, of which the following is a specification.

Nature and Object of the Invention.

My invention consists of certain improvements in straight-way stop-valves, fully described hereafter thereby, in which the valve proper, actuated by a screw, is caused to permit or prevent the direct flow of fluid through two branches of the casing.

The main objects of my invention are the economizing of labor and material in valves of this class, and of affording ready means of regrinding the valve to its seat.

Description of the Accompanying Drawing.

Figure 1 is a vertical section of a straight-way stop-valve, showing my improvement;

Figure 2, the same, showing the valve elevated;

Figure 3, the same, showing the manner of introducing the valve, part of the casing being detached;

Figure 4, a transverse section on the line 1 2, fig. 2; and

Figure 5, a perspective view of the valve proper.

General Description.

As regards general conformation, my improved stop-valve bears a resemblance to other stop-valves of this class, there being a casing, A, into which the valve can be elevated or depressed by turning a screw, B, and the casing having two branches, D D'

One of the branches D is detachable, for the introduction of the valve E to its place from below instead of from above, and the inner end of this branch projects a short distance into the interior or chamber of the casing, and against this face or seat the valve E bears when depressed, as shown in fig. 1.

The shape of the valve will be clearly understood by reference to the perspective view, fig. 5—

b, being the circular face;

d, the nut portion, having a threaded opening for receiving the screw B; and

e e, two ribs for bearing against inclined ribs f f, in the casing.

The action of the valve is as follows:

On turning the screw in one direction, the valve is elevated into the chamber of the casing A, thereby permitting a direct flow of fluid through the branches, and on turning the screw in a contrary direction the valve is depressed, and bearing with its rear against the inclined ribs f f, has its face b brought into right contact with the end a of the detachable branch D, so as to prevent the further flow of fluid through the branches.

The stem B' of the screw B passes upward through a cap, F, having internal screw-threads adapted to ex-

ternal screw-threads on a permanent projection of stuffing-box, G, on the top of and forming a part of the casing A, the said projection having a recess, to the bottom of which a collar, h, on the screw-stem is confined by the screw-cap F and intervening packing contained in the recess, as will be readily understood by reference to the drawing.

When the valve has to be introduced into its place, the screw-cap F is detached and is elevated with the screw, as shown in fig. 3, the branch D being also removed, so as to permit the insertion of the valve into the chamber of the casing in the inclined position shown in fig. 3, after which the valve is adjusted to its proper vertical position so as to receive the screw, which is now depressed and turned until the several parts assume the position shown in fig. 1, when the branch D is replaced, and the valve is in working order.

It will be readily understood without explanation how the valve may be withdrawn when necessary.

The advantages of my invention may be explained as follows:

In ordinary valves of this class the valve is used only in combination with a wedge or its equivalent, inasmuch as it is difficult to obtain a perfect bearing both on the inclined ribs f, and against the valve-seat, the wedge and valve moving slightly upon each other so that each can fit closely to its bearing.

By the use of a detachable branch D, in connection with a valve having inclined projections e secured to or forming part of the same, the necessity of employing a wedge is avoided, inasmuch as any imperfection in the fitting of the valve; either against its seat or on the inclined ribs f, may be readily corrected, owing to the ease with which access to the valve may be obtained.

Valves operating vertically, so as to be raised into a chamber above the direct water-passage, have hitherto been liable to objection in consequence of the difficulty of refitting after the seat or valve becomes worn; a difficulty which is effectively obviated by the use, in connection with such valves, of a detachable stem, having a seat at its inner end.

It will be seen that the threaded nut d is fitted loosely to the valve, so as to be readily detached and replaced, should the threads become worn, and so as to permit a slight play of the valve independent of the spindle, lateral pressure against the latter being thus avoided.

I do not claim, broadly, a valve-casing having a detachable branch, nor do I claim forming a valve-seat on the end of such branch; but

I claim—

1. The combination in a straight-way valve of a

casing, A, having a permanent branch, D', and detachable branch D, with a valve-seat at its inner end, inclined ribs f f, and a valve, E, having a vertical motion on a spindle, B, and which, on being depressed, is caused to bear directly on the said ribs, and against the end of the detachable branch D, all as set forth.

2. The valve E, having a vertical face, b, and inclined at the rear, in combination with a vertical seat, a, inclined lugs f, vertical rotating spindle B, and nut

d, sliding on the valve and receiving the spindle B, all as set forth.

In testimony whereof I have signed my name to this specification in the presence of two subscribing witnesses.

HENRY BELFIELD.
